United States Patent Office

Des. 207,785
Patented May 30, 1967

207,785

VEHICULAR TOY OR SIMILAR ARTICLE

Jarvis W. Rockwell, Chicago, Ill., assignor to Playskool
Manufacturing Company, Chicago, Ill., a corporation of Illinois

Filed July 5, 1966, Ser. No. 2,943

Term of patent 14 years

(Cl. D34—15)

The dominant features of the design reside in the portions shown in full lines.

I claim:

The ornamental design for a vehicular toy or similar article, as shown and described.
